UNITED STATES PATENT OFFICE.

EDWARD A. KING, OF DORCHESTER, MASSACHUSETTS, ASSIGNOR TO LION COLLARS & SHIRTS, INC., OF TROY, NEW YORK, A CORPORATION OF NEW YORK.

COLLAR.

Application filed October 10, 1922. Serial No. 593,501.

To all whom it may concern:

Be it known that I, EDWARD A. KING, a citizen of the United States, residing at Dorchester, in the county of Suffolk and State of Massachusetts, have invented a new and useful Improvement in Collars, of which the following is a specification, reference being had therein to the accompanying drawings.

10 My invention relates particularly to collars of the folded-over type and especially to "soft" or unstarched collars; it is also applicable, however, to collars that are intended to be starched.

15 Its principal object is to provide a collar that can be made with minimum waste of material and by a minimum number of operations, and to these ends it contemplates the production of the neck-band from a cloth 20 or cloths woven of exactly the proper width to permit the selvage of the cloth or cloths (e. g. the edges as finished in the cloth-constructing processes to prevent unravelling) to form the upper and lower edges of the 25 neck-band. This minimizes waste in cutting the material, renders it unnecessary to trim and turn the long upper and lower edges of the neck-band, permits a number of the manufacturing operations to be carried on simultaneously, and secures other 30 advantages. The narrow cloth may be woven with its longitudinal axis slightly curved, if desired, to conform the collar to the natural curve of the neck and may be 35 made of suitable material and weave to meet the current fashions and the fancies of the wearers, and the demands of the trade. A desirable button-hole arrangement is also illustrated in the accompanying drawings,

40 but is not essential to the present invention; this arrangement of the button-holes is the subject of a copending application. Other objects of the present invention will appear hereafter.

45 In the accompanying drawing, Fig. 1 is a perspective of a folded-over collar made in accordance with my invention.

Fig. 2 is an elevation of the same collar, a portion being broken away to show the 50 construction.

Fig. 3 is a cross section of the collar of Fig. 1.

Fig. 4 is a similar cross section of a collar in which the neck-band is made of but one 55 layer of fabric.

In the drawings illustrating my invention, the collar comprises a neck-band portion 7 and a top or folded-over portion 8, the band having the end extensions 9 and 10, with the usual button-holes 11 and 12, 60 and a button-hole 13 at the back of the band, which constitute the ordinary means for fastening the collar to the shirt.

The neck-band 7 is made of one or more layers of cloth 14 woven of exactly such 65 a width that the selvaged edges of the cloth form the longitudinal or long top and bottom edges 15 of the neck-band, i. e., the width of the cloth as woven is exactly equal to the width of the blank 14 (or each blank) 70 composing the neck-band. In the manufacture of this collar, therefore, it is not necessary that the bottom edges 15 and the upper long edges of the neck-band be turned in or otherwise "finished," for the finish of 75 the selvaged edges of the narrow cloth 14, which is the direct result of the weaving processes, is sufficient finish for the neck-band. The ends of the neck-band are finished, however, in any suitable manner, say 80 by turning in and sewing as shown, since the cutting of the narrow cloth into neck-band lengths leaves these edges rough. If a collar is desired in which the neck-band is slightly curved along its longitudinal axis 85 24, as shown in Fig. 2, to conform it to the neck of the wearer, the narrow cloth is woven on this curve. The cloth may be of any suitable or desirable material and weave. 90

The top or folded-over portion 8 of the collar is made of any suitable material and weave and may be of one or more thicknesses of fabric.

When two or more separate layers are 95 used in the folded-over portion 8 the edges thereof may be finished by inturning at the ends and bottom of the fold-over, and sewn as represented by the line or lines of stitching 18. For "soft" collars, however, I prefer to use a single layer of cloth for the fold-over and finish its raw end and bottom edges by binding with a thin fabric 20 stitched thereon and then inturning and securing to the body of the fold-over by the stitching 100 18 (Figs. 3 and 4). Preferably the binding 20 is also a tape or cloth woven of exactly 105 the desired width, so as to have two selvaged edges, and after this has been sewn to the collar edge and the latter turned in, one of 110

the stitching rows 18 may be made to coincide with the binding stitching and thus the latter is concealed. The use of tape 20 for this binding fabric not only renders inturning of the binding unnecessary and reduces the manufacturing cost, but also it permits the use of a single binding strip for the entire length of the fold-over without unduly increasing the cost, and thus avoids the presence of seams joining the customary short length of bias-cut binding material and the fraying and wear at the seams joining the short lengths, which is detrimental to the appearance of collars as heretofore commonly constructed. The fold-over 8 may be secured to the neck-band in any suitable manner. When but a single cloth 14 is used for the neck-band (Fig. 4) I secure the upper edge of the fold-over to the neck-band cloth by a double row of stitching 22, as shown in that figure; preferably the fold-over is then cut from a cloth that provides a selvage at the edge 23, so that inturning or other finishing of this edge is avoided. In the preferred construction in which the neck-band is formed of two layers of cloth (see Fig. 3) the edge 23 of the fold-over is inserted between the upper edges of the neck-band cloth and secured by double stitching 22. I also customarily employ a middle line of stitching, as indicated at 24.

The illustrated arrangement and provision of additional button-holes 26 and 27 is the subject of the copending application above referred to and forms no part of the present invention.

It will be observed that my present invention materially reduces the amount of fabric wasted in the course of manufacture; no fabric is wasted in making the neck-bands from cloths woven of the same widths as the neck-band blanks, except a little at the ends. Furthermore, the use of a fabric woven so narrow that its selvages form the upper and lower edges of the neck-band does away entirely with one of the regular steps in the customary collar-making processes, namely the step of inturning or infolding the long upper and lower edges of the pieces forming the neck-band in order to provide a non-raveling finish for those edges. Other advantages also follow from my invention as will be understood by those skilled in the customary collar-making art. A particularly important characteristic of my invention however is the thinness of the crease, ridge or fold at the top of the collar. By using two layers of fabric in the band and inserting the top or fold-over member between them as illustrated in Fig. 3, using the natural selvage of the cloth at the upper edge of the band for finish, I have found that it is possible to employ such heavy fabric as to make an acceptable "soft" collar, that is to say, one that will

remain erect and smooth in use without the aid of considerable starch, unlike the ordinary "starched" collar, and at the same time one that possesses such a narrow crease or ridge at its upper edge as to be generally acceptable to the trade and the customer. The provision of selvage at the upper edge only of the band accomplishes this purpose.

It will be understood that the illustrated and described embodiments of my invention are representative, and that my invention is not limited thereto except as hereinafter appears in the claims.

What I claim is:—

1. A folded-over collar having a neck-band comprising cloth having woven selvages and which is woven of the same width as a band blank so that the said selvages of the cloth form upper and lower edges of the neck-band. 80

2. A folded-over collar having a neck-band made from cloth having its edges finished in the cloth-contracting processes and which is woven of exactly such width that the said selvages of the cloth form the longitudinal edges of the neck-band. 90

3. A folded-over collar having a neck-band made from cloth having woven selvages and which is woven of such width that its said selvages form upper and lower edges of the neck-band, said cloth being constructed to have a curve corresponding to the curve in the finished collar. 95

4. A folded-over collar having a neck-band made up of two pieces of cloth each of which has woven selvages and is woven of such a width that its said selvages form upper and lower edges of the neck-band, and a folded-over portion secured to said neck-band between said pieces of narrow cloth. 100

5. A folded-over collar having a neck-band made up of two pieces of cloth each of which has woven selvages and is woven of such a width that its said selvages form upper and lower edges of the neck-band, and which are woven on a curve corresponding to the curve in the finished collar, and a folded-over portion secured to said neck-band between said pieces of narrow cloth. 110

6. A folded-over collar comprising a neck-band made of cloth having woven selvages and which is woven of such a width that its said selvages form the upper and lower edges of the neck-band, and a folded-over portion having a woven selvage edge secured to said neck-band. 115

7. A collar comprising a neck-band made of cloth having woven selvages and which is woven of a width corresponding to the width of the neck-band so that the said selvage edges of said cloth form the long upper and lower edges of the neck-band, and a separate fold-over attached to the neck-band. 125

8. A collar consisting of a band portion and a top or fold-over portion, the band 130

portion comprising two separate layers of fabric joined together, the upper edges of said layers being selvage edges of substantially the same thickness as the body of the 5 fabric and said top portion being inserted and secured between said selvage edges.

9. A collar consisting of a band portion and a top or fold-over portion, the band portion comprising two separate layers of fabric 10 the upper edges of which are selvages pro-

duced in the cloth constructing processes and said selvages providing the finish for the upper edge of the band, the said top portion being inserted between the said layers of fabric of the band, and the top and band 15 fabrics being secured together.

In witness whereof, I hereunto set my hand this ninth day of October, 1922.

EDWARD A. KING
